UNITED STATES PATENT OFFICE.

VICTOR D. JOHNSON, OF AURORA, ILLINOIS.

AUTOMATIC DRAWBRIDGE-GATE.

SPECIFICATION forming part of Letters Patent No. 668,610, dated February 19, 1901.

Application filed May 17, 1900. Serial No. 17,030. (No model.)

To all whom it may concern:

Be it known that I, VICTOR D. JOHNSON, a citizen of the United States, residing at Aurora, county of Kane, State of Illinois, have 5 invented a new and useful Improvement in Automatic Gates for Drawbridges, of which the following is a specification.

The objects of my invention are to provide a gate which automatically opens and closes 10 by the opening and closing movement of the drawbridge, and is more particularly adapted for bridges swinging upon a central pier. The mechanism is illustrated in the accompanying drawings, in which—

15 Figure 1 is a vertical elevation of the gate and its supporting ends, one side broken away. Fig. 2 is a plan view, one part broken away to show the working parts underneath. Fig. 3 is a detail of the gate. Fig. 4 is a vertical 20 view of the gate, showing tripping mechanism of the device for locking the parts. Fig. 5 is a detail of the rack and pinion, taken on line 5 5, Fig. 1. Fig. 6 is a vertical section of drum or reel on line 6 6, Fig. 2. Fig. 7 is 25 a vertical section on line 7 7, Fig. 2. Fig. 8 is a vertical section of the reel carrying the gate.

Similar numerals refer to similar parts throughout the several views.
30 The construction of the invention contemplates a double structure or a duplication of parts, one on each side of the roadway, and represented by 1 1, from which the gate is thrust outward. The gate comprising duplicate parts, each part is designed to be operated from one side of the roadway to the center by means of the operative mechanism contained in structure 1, hereinafter described, for thrusting the gate forward to the middle 35 of the roadway. Each of the two parts of the gate, which is flexible, is made up of separate vertical sections 3, Fig. 3, hinged together at top and bottom, so as to swing inwardly on the loose bolts 4. The gate is provided 40 with open spaces 5 above and below at regular intervals for two purposes—first, for a means of operation, and, second, to reduce its weight. For the latter purpose open spaces are also shown above and below the central 45 line. The object of dividing each part of the gate into vertical sections is to make it flexi-

ble to enable me to coil or wind it upon a reel 6, contained in the structure 1. The reel 6 has a vertical shaft 12 extending from the base up through the structure 1, and is operated by means of a rack 7 underneath the end of the drawbridge which engages with a pinion 8 and spur-gear 9, anchored in bearings in the abutment, as shown in Fig. 5. The spur-gear 9 is connected by pitmen 10 with a 55 sliding rack 11, set edgewise in bearings underneath the structure 1. The pitmen 10 being attached to one side of the gear 9 by the crank-pin 12' secures a movement of the racks 11 equal to the diameter of the spur-gear. 60 The vertical shaft 12, above mentioned as erected through the structure 1 and reel 6, is provided at its base with a spur-gear 13. A pinion 14, engaging with the rack 11, communicates the motion from the rack 11 to the 65 spur-gear 13 and the vertical shaft 12 in one structure, while an intervening idler 15 is used to provide a reverse movement in the other, which is required in order that the shafts 12 may have a uniform direction with 70 that of the mechanism on the opposite side of the roadway. Each of the shafts 12 carries the reel 6, upon which is carried one of the parts of the gate, one end of which is attached to the reel. The outward movement 75 of the rack 11 causes the drum 6 to revolve, unwinding the coiled gate, thrusting it out of its housing in a straight line toward the center of the roadway. A shaft 16, erected vertically on the arms 24 at the head and base 80 of reel 6, is provided with a gear 17 above and below, which engage in the open spaces 5 in the gate and serve as guides for the gate during the movement in either direction. A pinion 17' on the base of the shaft 16 engages 85 with an idler 17' on a contiguous vertical shaft 16', erected on the projecting arms 24 from the head and base of said reel, which transmits motion from the spur-gear 31 on shaft 12 to said shaft 16 to facilitate the outward movement of the gate and aid the movement of the reel. A shaft 18', also erected in 90 said arms 24 on the outer side of the gate and carrying gear-wheels 18 to engage with the gate, guides it in its outward thrust across 95 the roadway in a straight line. These gears 18 acquire their motion by contact with the 100

gate. A latch 19' is pivotally attached to each of the gate-sections 3 at their central line and carries a lug 21 at one end and a projecting pin 23' at the other. A block 20 is attached to one side of each of the gate-sections on a line with the latch 19'. The latch 19' is adapted to drop down between the blocks 20 on the gate-sections, permitting the lug 21 to engage with the under side of the block 20 on the same gate-section and the opposite end of the latch to engage with the side of the block 20 on the adjoining gate-section to hold said gate-sections inflexible in a direct or straight line.

15 The projecting pin 23' on the end of the latch 19' engages with the inclined groove 23 in the side 19 at the entrance to the housing, by means of which the gate-sections are locked or released according to the direction 20 the gate may be moved, whether in or out. The latch 19' when released is maintained in that position by the center piece 20' on the central portion of the reel after passing the groove 23.

25 Two wheels 25, carried rigidly on the shaft 12, provide the two heads of the reel 6 and are placed at a suitable distance apart to accommodate the height of the gate. The edge of the wheels is provided with a flange which 30 engages with the projecting shoulders upon the sides of the gate-sections provided by the members 3, by means of which the gate is carried and wound upon the reel. Two or more upright bars connect the two heads or 35 wheels 25. A center piece 20' extends around the reel to provide additional strength and also engages the pin 23' to prevent the latch 19 dropping down after leaving the groove 23.

40 A cable 26 supports the free ends of the gate when it closes the roadway. The cable is passed over a pulley 27, erected on a post on the structure 1, thence to another pulley 28 at the head of the reel. The slack is provided for by a sheave 29, mounted rigidly on shaft 12 above the reel, and partakes of the 45 same movement, carrying the end of the cable around with it. A signal-tower 30 may be erected upon the structure 1 and connected with the shaft 12, which is tubular and 50 through which the signal may be operated by any simple device connected with the movement of the reel, the movement in one direction to display the signal that the draw is open, the reverse that it is closed.

55 In the operation of the gate the swinging of the drawbridge gives motion to the spur-gear 9, which operates the pitman 10, giving motion to the rack 11 and incidentally to the shaft 12 by the intervening pinion and spur 60 13, which operate the wheels 25 and 31, connected with the operation of the gate. The wheels 25, being turned by the shaft 12, thrust the gate forward, aided by the gear-wheels on shaft 16 and spur-gear 31, while the guide-wheels on shaft 18' direct the gate across the roadway. The bridge swinging back to its 65 normal position, rack 7 engages with spur-

gear 9 and reverses the movement of the reels, which then withdraw the gate and coil it again. As the gate passes out of its housing 70 the latching device is automatically operated by the groove at the side, making the gate-sections inflexible. The reverse movement releases the latch to permit the gate to adapt itself to the reel on which it is carried.

Having thus described my invention, what I claim as new, and desire to protect by Letters Patent, is—

1. In an automatically-operated gate for drawbridges the combination with a drawbridge of a two-part flexible gate, each part consisting of vertical sections hinged together to permit it to be coiled in one direction, a reel for each of said parts erected upon each side of the roadway, a flanged wheel on each 85 head of said reel adapted to carry said gate, a housing for said reel, a means for operating said reel to thrust each of said gates to the center of the roadway automatically by the movement of said drawbridge, and means 90 for automatically inflexibly locking said gate-sections as the gate is ejected from the reel.

2. In an automatically-operated gate for drawbridges, a two-part flexible gate, each part consisting of vertical sections hinged together and adapted to be coiled in one direction, a reel for each of said parts erected upon each side of the roadway, each of the 95 said reels adapted to coil and carry one part of said gate, a vertical shaft for said reel, a rack underneath the end of the drawbridge, a pinion and spur-gear anchored in the abutment to said drawbridge to engage said rack, a pitman connecting said spur-gear with a sliding rack at the base of said vertical shaft, 100 a spur-gear on the base of said vertical shaft, a pinion to engage said spur-gear and said rack substantially as described.

3. In an automatically-operated gate for drawbridges, a two-part gate, each part consisting of vertical sections hinged together, a block at a central point in each of said vertical sections, a locking device pivoted adjacent said block and adapted to drop between the blocks of contiguous sections to lock such 115 sections inflexibly together, means for releasing said locking device automatically during the operation of said gate substantially as specified.

4. In an automatically-operated gate for 120 drawbridges, a drawbridge, a rack underneath the end of said drawbridge, a spur-gear anchored in bearings in the abutment to said bridge to engage said rack, pitmen attached to one side of said spur-gear having 125 a horizontal movement equal to the diameter of said spur-gear, a horizontal sliding rack at the end of said pitmen, a pinion and spur-gear to engage said sliding rack, a vertical shaft for said spur-gear, a reel rigid on said 130 vertical shaft, a gate hinged in sections around said reel adapted to be moved outward from said reel in a straight line, guides for said gate, means for inflexibly locking and

unlocking said gate-sections automatically as it leaves and returns to said reel, substantially as specified.

5. In an automatically-operated gate for drawbridges the combination of a drawbridge having a rack underneath the end thereof, with a spur-gear and pinion anchored in bearings in the abutment, pitmen attached to a crank-pin in one side of said spur-gear and having a horizontal movement, a rack set edgewise and adapted to move horizontally on the same plane with each of said pitmen and attached to the free end of said pitmen, a pinion and spur-gear to engage said rack, a vertical shaft for said spur-gear, a reel rigid on said shaft, a gate comprising vertical sections flexibly hinged together adapted to be coiled and carried upon said reel, vertical shafts carrying gear-wheels as guides for said gate, a housing for said reel and gate, a locking device for said gate-sections, means for automatically operating said locking device substantially as specified.

20 6. In an automatically-operated gate, the

combination of a two-part gate divided into 25 vertical sections hinged together, with a housing for each part of said gate on the side of the roadway, a vertical shaft erected in said housing, a reel rigid on said vertical shaft, a wheel having a flange at the head and base of 30 said reel, adapted to engage a shoulder or projecting sides of said gate, vertical shafts carrying gear-wheels as guides for said gate a spur-gear at the base of said first-mentioned vertical shaft, a pinion to engage said spur- 35 gear, a horizontal rack to engage said pinion, a pitman having a horizontal movement to give motion to said rack, a spur-gear at center of roadway engaging said pitman, a drawbridge having a rack underneath the end to engage 40 said spur-gear substantially as specified.

In testimony whereof I affix my signature in presence of two witnesses.
